UNITED STATES PATENT OFFICE.

SANTE FAZZINI, OF NEW YORK, N. Y.

PAPER-HANGER'S KIT.

1,223,161.

Specification of Letters Patent. Patented Apr. 17, 1917.

Application filed December 8, 1916. Serial No. 135,760.

To all whom it may concern:

Be it known that I, SANTE FAZZINI, a subject of the King of Italy, and a resident of the city of New York, borough of Manhattan, in the county and State of New York, have invented a new and Improved Paper-Hanger's Kit, of which the following is a full, clear, and exact description.

This invention relates to kits or traveling cases for paper hangers or other workmen, but having reference especially to paper hangers' appliances whereby they may conveniently carry with them all of the tools or appliances ordinarily used.

15 Among the objects of the invention is to provide a collapsible kit or case which in one position, as for transportation, is adapted to hold all of the tools ordinarily used by the paper hanger, except possibly his straight edge, the kit or case in this position simulating an ordinary suit case in size and appearance, but the kit is so constructed that when it is opened out it will provide a complete cutting and paste-applying table.

25 Another object of the invention is to provide a kit for paper hangers whereby they are enabled to carry with them all of their appliances without being subjected to delay or annoyance due to the fact that paper hangers' devices as ordinarily used and carried are too cumbersome and unsightly to be admitted to street railway cars or other public conveyances.

35 With the foregoing and other objects in view the invention consists in the arrangement and combination of parts hereinafter described and claimed, and while the invention is not restricted to the exact details of construction disclosed or suggested herein, 40 still for the purpose of illustrating a practical embodiment thereof reference is had to the accompanying drawings in which like reference characters designate the same parts in the several views, and in which—

45 Fig. 1 is a perspective view showing my apparatus open for use as a table, all of the parts being in place except the straight edge which is left aside to better disclose the construction of the case or kit;

50 Fig. 2 is a bottom plan view of the main portion of the kit, the kit being open and showing the tools in carrying position therein and also the legs in their closed position;

55 Fig. 3 is a vertical transverse section of

the device closed with all the parts in carrying position;

Fig. 4 is a longitudinal sectional detail on the line 4—4 of Fig. 3, showing the manner of locking the legs in carrying position;

Fig. 5 is an end view of the table partly broken away to show the manner of securing the legs in supporting position; and

Fig. 6 is an end view in detail indicating the manner of securing the straight edge to the table.

Referring now more particularly to the drawings, I show a kit comprising two substantially similar parts 10 and 11 hinged together end to end at 12, so as to simulate a suit case when closed. I indicate at 13, a sliding bolt carried by one of the sections of the kit and movable into engagement with the other to temporarily hold the sections open or in extended position. Within each of the sections and adjacent to the end remote from the hinge line, I provide a pair of blocks 14 and 15 of a depth equal to the open space within such sections. These blocks serve several important functions. First, they constitute socket pieces for the legs described below, each block having a hole or socket 16, preferably screw threaded. The blocks also stiffen and reinforce the kit construction. Again, the blocks 15 are notched out at 17 at their outer lower portions in alignment with the cutaway 18 formed in the lower outer portions of the sections 10 and 11.

The four legs 19 are carried two in each section. The legs being slightly longer than the length of the interior of the sections, the ends of the legs are extended into sockets 20, as indicated in Fig. 4, while the opposite end portions of the legs fit into the cutaway 17 of the block 15 carried by such section. The width of two legs is such as to just fill the space between the edge or bottom panel 21 of the section and the free edge 22 of the side panel of the same section. By reference to Fig. 1, it will be understood that the outside of the kit becomes the table top and that the legs are put into place for transportation from the outside. The upper ends of the legs are threaded at 23 for cooperation with said threaded sockets 16 of the blocks 14 and 15. That portion of the threaded ends of the legs received into the cutaways 17 is provided with a transverse

hole 24 through which a locking pin 25 is adapted to be projected downwardly from the inside of the kit. The lower ends of the pins project into the bottom panels 21 of the 5 kit. These pins, together with the coöperation between the opposite ends of the legs and the sockets 20, positively hold the legs from falling out of place in transportation.

A suit case being ordinarily of a size 10 providing too narrow a table for practical purposes, I employ a flap 26 for the outside of each section, the same being hinged at 27 along a line just below the upper portion of such section. These flaps 26 are 15 made preferably of thin sheet metal and hence the offset incident to hinging them upon the outer panels of the kit is practically negligible. The width of the panels is such that their outer or free edges drop 20 adjacent to the edges of the panels 21 in transportation and hence overlap the outer faces of the legs. When opened out, however, the flaps 26 extend in practice a foot or so beyond that portion of the kit which 25 is the top thereof when in carrying position, giving ample width to the table for a paper hanger's use. The flaps 26 are supported in extended position by means of a pair of V-shaped yokes 28, each made of 30 spring material and having the form indicated in dotted lines in Fig. 2, the ends of each yoke being fitted into socket pieces 29 adjacent to the handles 30. These yokes are shown in collapsed or nested position 35 in full lines in Fig. 2 carried along with other tools within the kit.

The only lengthy appliances carried by the paper hanger in connection with this kit are the straight edge 31 and a cutting plate 40 32, each having a length equal to the extended length of the kit. These parts, however, being comparatively small and light are not difficult to manage along with the kit. The plate 32 may be fitted upon the 45 table top at the open space indicated in Fig. 1 and as shown complete in Figs. 5

and 6 to make a finish for the table and is snubbed or held in operating position by means of turn buttons 33 or their equivalent. The straight edge is adapted to be 50 used for its usual purposes while the paper is being trimmed or cut on the plate.

I claim:

1. In a paper hanger's kit, the combination of a pair of similar sections hinged together end to end, reinforcing and stiffening means for said sections comprising a set of blocks secured within the same, each of the blocks having a threaded socket, a set of legs carried within the kit when collapsed, each leg having a threaded end adapted to coöperate with the socket in one of the blocks, one block of each section being cut away from one side to receive certain of the legs in carrying position, and a member passing through the cutaway block to lock the legs therein. 55

2. The herein described paper hanger's kit comprising a pair of box-like sections hinged together end to end, portions of the 70 sections being cut away along one outer edge, supporting legs for the device when extended, said legs comprising two for each section adapted to be carried within the same in transportation and serving to fill 75 the cutaway space aforesaid, and means to lock the legs in fixed position.

3. In a paper hanger's kit, the combination of a pair of similar box-like sections hinged together end to end and adapted to 80 fold together providing an inner space for tools, said sections, however, being adapted to be extended to form a table top, means to lock the sections extended with their outer faces upward in horizontal position, 85 said outer faces being cut away along one edge, a set of supporting legs for the table top carried normally in transportation in said cutaways, and a cutting plate serving to fill said space when the device is used, 90 as a table.

SANTE FAZZINI.
